UNITED STATES PATENT OFFICE.

JOHN F. BEANS, OF CANTON, OHIO, ASSIGNOR TO THE BEANS SPRING COMPANY, OF MASSILLION, OHIO, A CORPORATION OF OHIO.

DIE.

Application filed November 29, 1921. Serial No. 518,518.

To all whom it may concern:

Be it known that I, JOHN F. BEANS, a citizen of the United States, residing at Canton, in the county of Stark and State of Ohio, have invented a new and useful Die, of which the following is a specification.

This invention relates to improvements in dies and more particularly to dies for shearing, punching and trimming steel spring plates such as are used for vehicle springs.

With devices of this kind at present in use, it is customary to first shear the steel plates, then punch the center holes therein upon another machine, finally trimming the ends of the plate upon a trimming press, four distinct operations being necessary to complete each spring plate or leaf.

The objects of the invention are to provide a die adapted to cold shear, trim and punch steel spring plates or leaves, forming a complete plate or leaf with each operation.

With these objects in view, the invention consists in the construction and arrangement of parts, hereinafter described and illustrated in the accompanying drawings, it being understood that various changes in the form and details of construction may be made within the scope of the appended claims.

A preferred embodiment of the invention is disclosed in the accompanying drawings, in which—

Figure 1 is a side elevation of a portion of a press showing the dies embodying the invention mounted therein, the upper die being shown in its lowered position, a spring plate or leaf being located between the dies;

Fig. 2, a side elevation of the upper die, parts being broken away for the purpose of illustration;

Fig. 3, a bottom plan view of the same;

Fig. 4, a section on the lines 4—4, Figs. 2 and 3;

Fig. 5, a top plan view of the lower die;

Fig. 6, a section on the line 6—6, Fig. 5;

Fig. 7, a section on the line 7—7, Figs. 5 and 6;

Fig. 8, a longitudinal sectional view through both dies in the closed position;

Fig. 9, a perspective view of the lower trimming and shearing dies, with one of the trimming dies removed; and

Fig. 10, a detached, perspective view of one of the lower trimming dies.

Similar numerals of reference indicate

corresponding parts throughout the drawings.

The device includes the lower stationary die comprising the shoe 1 which is arranged to be fixedly mounted upon the base or anvil of any suitable form of press, such as is indicated generally at 2, and the upper movable die comprising the punch holding block 3 which is carried in the reciprocating head 4 of the press and arranged to be moved toward and from the lower die by the operation of the press.

The upper surface of the shoe 1 is flat as shown at 5, the angular guide brackets 6 and 7 being mounted upon opposite sides of the longitudinal center thereof, preferably toward the end from which the stock A, from which the spring plates or leaves are stamped, is passed into the device.

For the purpose of clamping the stock against movement, upon the shoe, as the upper die descends, a lever 10 is pivoted near one end between the brackets 11 which are mounted upon the upper surface of the shoe. This lever is provided with the downwardly disposed, inner end 12 arranged to engage the adjacent side edge of the stock, forcing the stock against the opposite guide bracket 7 when the outer end of the lever is lowered. A counterweight 13 is mounted upon the outer end portion of the lever for the purpose of normally holding the same in position to engage the stock, a chain 14 connecting the outer extremity of the lever with the reciprocating head 4 of the press, providing means for raising the outer end 90 of the lever to disengage the inner end thereof from the stock when the reciprocating head is raised.

The shoe 1 is provided at its longitudinal center with spaced intervals with cylindric 95 sockets 15 which receive the punch buttons 16, the upper-extremities thereof extending above the upper surface of the shoe. Each of these punch buttons is provided with the downwardly flared central opening 17 communicating at its lower end with the enlarged bore 18 extending through the bottom of the shoe.

The lower trimming and shearing dies 19 are located in a socket 20 formed in the upper face of the shoe, each of said dies being of the shape best shown in Figs. 9 and 10, being provided upon their inner edges

with the cut-out portions 21 and the tapered extremity 22 and being fixedly attached to the shoe as by the filister head screws 23. The shoe is cut out around the tapered extremities of these dies as best shown at 24 in Fig. 5 for the purpose of receiving the upper trimming and shearing die as will be later explained.

Filler blocks 25 are mounted upon the upper face of the shoe upon each side of each die 19 and connected thereto as by the screws 26 which are passed through the stripper plates 27 and through said blocks and into the shoe. These stripper plates are of the shape best shown in Fig. 5, being provided with the reduced, tapered, inwardly disposed portions 28 located above the tapered portions 22 of the lower trimming and shearing dies. The stripper plates are thus spaced above the trimming and shearing dies a sufficient distance to permit the stock to be easily passed beneath the same.

Downwardly flared openings 29 are provided in the reduced portions 22 of the dies 19 and communicate at their lower extremities with the enlarged bores 30 extending through the bottom of the shoe 1. These downwardly flared apertures provide punch holes to receive the rebound hole punches, as will be later described, the stripper plates 27 being provided with enlarged openings 31 above said punch holes to allow the rebound punches to pass therethrough.

A pair of spaced gauge bars 32 are connected to the end of the shoe opposite from the punch buttons by means of the downwardly disposed angular portions 33, screws 34 or the like attaching the same to the extremity of the shoe. These gauge bars are located in alignment with the shoe 1, and are provided at spaced intervals with the apertures 35 arranged to selectively receive the screws 36 carried upon the gauge 37 for the purpose of locating this gauge at any desired distance from the shearing and trimming dies necessary for forming spring plates or leaves of different lengths.

The punch holder studs 38 are provided with the enlarged heads 39 received within the countersunk openings 40 provided in the punch holder plate 41 which is attached to the punch holder block 3 by means of the screws 42 or the like. These punch holder studs are located in positions corresponding with the punch buttons 16 and with the rebound punch openings 29.

The center hole punch 43 is arranged to be selectively connected to any of the punch studs 38, corresponding with the punch bottoms 16, by means of the punch holder nut 44. The rebound hole punches 45 which are similar in construction to the center hole punch, are mounted upon the corresponding punch holder studs by means of similar punch holder nuts 44.

The upper trimming and shearing die 46, as best shown in Fig. 3, is shaped to correspond with the reduced tapered portions 22 of the lower shearing and trimming dies and is connected to the plates 47, as by the rivet 48, said plates being located upon opposite sides of the die, the lower ends thereof extending beyond the bottom of the dies, these plates, together with the die 46, are arranged to be received through the opening 24 in the shoe, the end portions of the plates being received in the cut-out portions 21 of the lower shearing and trimming dies.

The upper ends of the die 46 and plates 47 are provided with the beveled flanges 48^a which are received in the countersunk opening 49 provided in the punch holder plate 41, this die being held in position upon the punch block 3 by means of the screws 42 which secure the punch holder plate to the block.

In operating the device, the reciprocating head 4 is raised in the usual manner, raising with it the punch block 3 and upper die, and through the chain 14, raising the outer end of the lever 10, permitting the stock A to be passed through the device between the guide brackets 6 and 7 and beneath the stripper plates 27. When the stock is placed in the proper location, the reciprocating head 4 is lowered in the usual manner, the counterweight 13 moving the outer end of the lever 10 downwardly as the chain 14 is slackened, bringing the inner curved extremity 12 of the lever into engagement with the edge of the stock, forcing the same tightly against the bracket 7 and holding the stock against accidental movement as the punch block and upper die engage the same.

It will be seen that with each operation of the device, the center hole and one rebound hole are punched and one end of a plate is formed and sheared, while at the same time, the opposite end of the next preceding leaf or plate is sheared and trimmed and the center hole punched. After each operation of the device, the stock is fed forwardly through the machine until the end thereof engages the gauge 37. A spring plate or leaf is thus completed with each operation of the device.

It will be seen that the center hole punch 43 may be mounted upon any desired punch holder stud, the gauge 37 being located accordingly in order to stamp spring leaves or plates of desired length. With the device shown, it will be seen that six different lengths of spring plate or leaf may be obtained by adjustment of the device.

The advantage over the usual method of forming spring plates or leaves will be readily apparent from the above, as the four separate operations of shearing, trimming, 130

punching the center hole, and punching the rebound holes are all combined in one single operation of the present device, and a complete spring being formed with each operation thereof.

I claim:-

1. A device of the character described including a fixed shoe, lower trimming and shearing dies near one end thereof arranged 10 to shear and trim opposite ends of two adjacent spring plates, each of the lower dies being provided with an aperture, a vertically movable block above the shoe, upper shearing and trimming dies arranged 15 to cooperate with the lower shearing and trimming dies and punches mounted upon the upper shearing and trimming dies arranged to engage said apertures to punch the rebound holes in opposite ends of the 20 spring plates.

2. A device of the character described including a fixed shoe, lower shearing and trimming dies near one end thereof arranged to shear and trim opposite ends of two adjacent spring plates, each of the lower dies 25 being provided with an aperture, a punch button near the other end of the shoe, a vertically movable block above the shoe, upper shearing and trimming dies arranged to cooperate with the lower shearing and 30 trimming dies and a punch upon said block arranged to cooperate with the punch button to form the center hole in a spring plate, and punches mounted upon the upper shearing and trimming dies arranged to engage 35 said apertures to punch the rebound holes in opposite ends of the spring plates.

In testimony that I claim the above, I have hereunto subscribed my name.

JOHN F. BEANS.
